(57) **CLAIM**

The ornamental design for an electrosurgical wand distal tip, as shown and described.

DESCRIPTION

FIG. 1 is a perspective view of an electrosurgical wand distal tip, showing our new design;

FIG. 2 is a perspective view thereof, from an alternate angle;

FIG. 3 is a perspective view thereof, from an alternate angle;

FIG. 4 is a bottom view thereof;

FIG. 5 is a first side view thereof;

FIG. 6 is a front view thereof; and,

FIG. 7 is a top view thereof.

The portion of the electrosurgical wand distal tip depicted in broken lines form no part of the claimed design. The second side view has been omitted as it is a mirror image of the first side view presented.
